UNITED STATES PATENT OFFICE.

HENRY MAYTROTT, OF NEW YORK, N. Y., ASSIGNOR TO MANHATTAN BRASS COMPANY, OF NEW YORK, N. Y., A CORPORATION OF NEW YORK.

GAS HEATER OR STOVE.

SPECIFICATION forming part of Letters Patent No. 745,287, dated November 24, 1903.

Application filed February 6, 1903. Serial No. 142,129. (No model.)

To all whom it may concern:

Be it known that I, HENRY MAYTROTT, a citizen of the United States, residing at the borough of Brooklyn, in the county of Kings, 5 city and State of New York, have invented an Improvement in Gas Heaters or Stoves, of which the following is a specification.

My invention relates to a gas heater or stove of simple inexpensive construction and of 10 maximum radiation, with the object of effecting substantially perfect combustion with a minimum consumption of gas.

In carrying out my invention and in combination with a cylindrical metal case or drum 15 I employ a gas and air burner of peculiar form and a deflector-plate above the burner and beneath which the gas and air burn as a spread or disk-like flame covering approximately the area of the deflector-plate and 20 producing substantially perfect combustion without smell or smoke. The air is heated before entering the gas-pipe to be commingled with the gas, and the entrance of the air is protected from the flame. The cylindrical 25 metal case or drum with perforations near its respective ends is connected to a suitable base with supporting-legs and to a top with perforations, and between the edge of the deflector-plate and the inner surface of the cylindrical case or drum there is an annular 30 opening for the heated air.

In the drawings, Figure 1 is a vertical section illustrating my improved gas heater or stove. Fig. 2 is a sectional plan at xx of Fig. 35 2, and Fig. 3 is a vertical section at the upper end of the gas-pipe and through the burner structure in larger size.

a represents the cylindrical case or drum, preferably of sheet metal and provided near 40 its lower end with perforations 2 and near its upper end with perforations 3, which perforations may be given any form or desired outline.

b represents a sheet-metal base with a flange 45 receiving the lower end of the cylindrical case or drum a and with supporting-legs b' secured thereto.

c represents a sheet-metal top having perforations 4 in the central portion, and dd are 50 bolt tie-rods that pass through the top c within the cylindrical case or drum and through

the sheet-metal base b to securely connect the case or drum, the base, and the top into a permanent structure and apply tension thereto.

Within the cylindrical case or drum and rising from the central portion of the base is a pipe-standard e . This is secured to the base in any desired manner, and from the lower end of said pipe-standard extends a supply- 60 pipe e' in a horizontal direction through the sheet-metal base b , and in this pipe there is a gas-cock 5, controlling the supply of gas to the burner. At the upper end of the pipe-standard e there is a coupling 6. A sheet- 65 metal or Bunsen tube f is connected at its lower end to a coupling part that screws upon the coupling 6 and in which there is a small opening above the larger opening in the coupling 6.

In the base of the tube f there are perforations 7 for admitting air to be mixed with the gas that rises through the pipe-standard e and the couplings. Surrounding the smaller portion of the tube f there is an annular shield 75 g in the form of an inverted cup, the lower portion or skirt of which surrounds the perforations 7. The top part of the Bunsen tube is made with a horizontal imperforate portion f' and with an inclined portion 8, having 80 perforations.

Within the cylindrical case or drum a is a deflector-plate h of appreciably less diameter than the inner portion of said case or drum. This deflector-plate is preferably convex in 85 form and secured at the central portion by a screw 9 to the imperforate center of the Bunsen-burner tube, so that said plate is supported directly upon said tube and the pipe-standard e . In the operation of the structure gas 90 is supplied in a regulatable quantity through the gas-cock 5, supply-pipe e' , pipe-standard e , and air entering by the perforations 2 within the drum passes in through the perforations 7 of the Bunsen-burner structure in 95 liberal quantities and commingles with the gas passing upward, so that the tube f becomes a mixing-chamber. The gas strikes with force against the under surface of the imperforate top f' and is deflected through 100 the perforations of the part 8, around which the gas and air burn as a spread or disk-like

flame against the under surface of the deflector-plate *h*.

The air in the case or drum below the deflector-plate becomes heated and prepared for ready admixture with the gas to be consumed, and the shield *g* between the flame and the openings *7* protects said openings, so that the gas is not lighted within the pipe-standard *e* or the mixing-chamber tube *f*, but only after emerging through the perforations in the part *8*. A very hot blue-red flame is in this manner produced, the size of which is alone controlled by the quantity of gas passing in through the pipes to be consumed and the air that mixes therewith, it being a fact that the liberal openings provided make it possible for as much air to be commingled with the gas as can be taken up thereby. Consequently a flame in which there is substantially perfect combustion is produced, air in the case or drum above the deflector-plate *h* is heated, and a large proportion of the air that enters through the lower perforations *2* passes up the inside of the case or drum in the annular space between the said deflector-plate and drum, is highly heated in transit, and passes out through the openings *3* or through the openings *4* in the sheet-metal top *c* into an apartment to heat the same.

3. I claim as my invention—

1. A gas heater or stove, comprising a tubular cylindrical case or drum having perforations at the respective ends, a separable base for supporting the same, a perforated separable top, means within and longitudinally of the case for connecting said parts, a deflector-plate within said cylindrical case or drum and an air and gas burner beneath said deflector-plate, substantially as set forth.

2. A gas heater or stove comprising a base and supporting-legs, a separable cylindrical case or drum resting upon and rising therefrom, a separable perforated top, and tie-rods within and longitudinally of the case for connecting the top and the base to hold the case or drum in position, a horizontally-placed deflector-plate within said case or drum and of smaller diameter than the interior thereof so as to leave an annular space between the parts, a central pipe-standard passing through the base, and a pipe connected therewith for supplying regulatable quantities of gas, a gas and air burner at the upper end of said standard, and means for connecting the deflector-plate to said burner.

3. A gas heater or stove comprising a base and supporting-legs, a cylindrical case or drum rising therefrom, a perforated top and means for connecting the top and the base to hold the case or drum in position, a deflector-plate within said case or drum and of smaller diameter than the interior thereof so as to leave an annular space between the parts, a

central pipe-standard and a pipe connected therewith for supplying regulatable quantities of gas, a gas and air burner at the upper end of said standard, means for connecting the deflector-plate to said burner, there being openings in said burner for the entrance of air to commingle with the gas, and a shield covering and protecting said openings, and an inclined portion having perforations at the upper end of said burner beneath said deflector-plate.

4. In a gas heater or stove, a burner comprising a tubular portion with openings for air near the base, an imperforate upper end, an inclined portion having perforations between said end and tube and through which commingled air and gas pass to be burned, and a deflector-plate directly above the burner, so that a downward and outwardly extending disk-like flame is produced, substantially as set forth.

5. In a gas heater or stove, a burner comprising a tubular portion with openings for air near the base, an imperforate upper end, an inclined portion having perforations between said end and tube and inclined to a vertical plane, and through which commingled air and gas to be burned pass, so that a downward and outwardly extending disk-like flame is produced, and a shield of inverted-cup form surrounding the tubular part of said burner and covering and protecting the air-apertures.

6. In a gas heater or stove, a burner comprising a tubular portion with openings for air near the base, an imperforate upper end, an inclined portion having perforations between said end and tube and inclined to a vertical plane and through which commingled air and gas to be burned pass, and a deflector-plate having a recessed center directly above the burner so that the horizontal part of the said plate is appreciably above the burner so that a downward and outwardly extending disk-like flame is produced, and a shield of inverted-cup form surrounding the tubular part of said burner and covering and protecting the air-apertures.

7. In a gas heater or stove, a burner comprising a tubular portion with openings for air near the base, an imperforate upper end, an inclined or flaring portion between said end and the tubular portion and having perforations therein that are inclined to a vertical plane and through which commingled air and gas pass to be burned, so that a downward and outwardly extending disk-like flame of substantially even thickness is produced.

Signed by me this 3d day of February, 1903.

HENRY MAYTROTT.
